ABSTRACT OF THE DISCLOSURE

A target for a vidicon, orthicon or other television camera-type tube is provided having an evaporated layer of silicon monoxide or silicon dioxide on a nickel or other conductive screen wire or electroformed mesh. The evaporated layer is thus perforate at the holes in the mesh. A 1000 angstrom imperforate sheet of silicon monoxide or other dielectric is then fixed to the evaporated layer. The use of the thin sheet thus provides a high sheet-to-mesh capacitance for high resolution and a large dynamic range. However, the target is more rugged than is conventional because a molecular bond between the mesh and sheet increases rigidity.

The invention herein described was made in the course of or of a contract or subcontract thereunder, with the U.S. Army.

Background of the invention

This invention relates to the storage tube art, and more particularly to a rugged storage tube target having exceptionally good resolution and a wide dynamic range.

In the past it has been the practice to construct a storage tube target by stretching a thin film or dielectric in a frame therefor. Supported in this manner, the target is highly susceptible to damage through shock or vibration. Further, it is impossible to obtain good resolution and a wide dynamic range with such a target because it is not possible to make the film sufficiently thin for a large capacitance. This affects its charging capacity and therefore its dynamic range. A large accelerating voltage is also required for the primary electrons and this, in turn, can cause poor resolution because of arcing or a distorted screen electric field.

Summary of the invention

In accordance with the device of the present invention, the above-described and other disadvantages of the prior art are overcome by providing a storage tube target including a metal mesh having a perforate, evaporated layer of a first dielectric sandwiched between the mesh and a thin imperforate sheet of a second dielectric. The first dielectric is employed to provide a foundation bonded to the mesh to which a uniform bond may be made with the sheet. Although the evaporated layer has holes therethrough in registration with those of the mesh, the sheet covers these holes.

By the use of the target of the invention it is possible to make the sheet as thin as 1000 or 650 angstroms. The sheet-to-mesh capacitance is thus very large and the target has a large charging capacity which makes its dynamic range large. That is, the size of the gray or half-tone region of operation is increased. The large charging capacity also makes it possible to use what is known as a proximity focus. That is, a photosensitive surface may be located very near the sheet with a very low or zero primary electron accelerating voltage. The target may thus be properly charged without any attendant arcing or

2

distortion due to high screen fields, and resolution is improved.

Still further, in accordance with the invention, a molecular bond between the evaporated layer and the mesh and sheet makes the entire target have a high integrity. It is therefore not severely damaged when subjected to considerable vibration and shock.

The above described and other advantages of the present invention will be better understood from the following description when considered in connection with the accompanying drawing.

Brief description of the drawing

FIG. 1 is a side elevational view of a television camera-type tube partly in section;

FIG. 2 is a transverse sectional view greatly enlarged, of a storage target shown in FIG. 1.

Description of the preferred embodiments

20 In the drawing in FIG. 1, a storage tube is indicated at 10 having a glass envelope 11. A photosensitive coating 12 is provided on the end of envelope 11. A storage target is indicated at 13, and a collector grid is indicated at 14.

25 As will be explained, tube 10 may be operated as a vidicon or as an image orthicon. In the case of vidicon operation, collector grid 14 may or may not be omitted, as desired.

Tube 10 has an electron gun 15 for producing a scanning beam of electrons 16.

30 Tube 10 may be entirely conventional except for the construction and location of target 13.

Target 13 may be located sufficiently close to coating 12 so that a small or zero accelerating voltage may be applied between coating 12 and target 13. In other words, 35 a proximity focus may be employed. This is true because the charging capacity of target 13 is high. The manner in which such a high charging capacity is created is by the use of a very thin insulating sheet 17 shown in FIG. 2. Target 13 may include a metal mesh 18 made of a woven 40 screen of circular wires 19. Alternatively, mesh 18 may be an electroformed mesh having meshes of a square cross section.

In the construction of target 13, mesh 18 is supported 45 in a conventional clamp ring. It is stretched taut in the ring. A layer of silicon monoxide 20 is then evaporated on one side of mesh 18 by use of any conventional evaporation process. In lieu of silicon monoxide silicon dioxide may be employed, if desired. The thickness of the dielectric at 20 is not critical but is preferably at least one 50 micron and not greater than 50 microns. Mesh-to-sheet capacitance decreases with increased dielectric thickness. Structural strength and dielectric resistance to arcing and the like decrease with decreased dielectric thickness.

Sheet 17 is fixed to the dielectric at 20. The dielectric 55 at 20 may be bonded to mesh 18. Sheet 17 may then be bonded to dielectric 20. In other words, dielectric 20 may have a molecular bond with both. Further, if desired, sheet 17 may be additionally clamped to dielectric 20 by conventional clamp rings welded together as indicated at 21 and 22 in FIG. 2.

Mesh 18 and sheet 17 may be made from any one of several materials. Sheet 17 may also be fixed to dielectric 20 by any conventional method. For example, mesh 65 18 may be made of nickel, copper, silver or gold, or any alloy thereof. Sheet 17 may be made of silicon monoxide, silicon dioxide, aluminum oxide, potassium chloride, sodium bromide, or magnesium oxide.

Mesh 18 should be as fine as possible. It preferably has at least 500 and preferably 1000 or 2000 or more lines per inch. However, the mesh becomes structurally weaker if it is finer than 2000 lines per inch. Sheet 17 preferably has a

thickness of about 1000 angstroms. However, this thickness is not critical. For example, an electroformed sheet of Al_2O_3 of a thickness of 650 angstroms may be employed. The aluminum oxide sheet may be electroformed in the conventional way. In general, the aluminum oxide sheet will be supported on the surface of quantity of water. Mesh 18 will be supported below the water's surface in a pan with dielectric 20 on the upper side of the mesh. The water is drained out and the sheet 17 is then lowered onto dielectric 20 in a manner similar to that used in the prior art in preparing phosphor screens.

In an alternative embodiment, a drop of lacquer consisting essentially of any conventional nitrocellulose in a solvent is placed on top of the surface of a quantity of water having an upper surface dimension of 12 in. by 18 in. The film sets to a fairly hard state almost immediately. The water is then drained to allow the film to deposit on dielectric 20 as before. Silicon monoxide may then be evaporated on to the lacquer film by a conventional process. The target is then baked until the lacquer is evaporated. This will produce sheet 17 of silicon monoxide having a molecular bond to dielectric 20, which also may be made of silicon monoxide.

A typical woven nickel wire mesh of 1000 lines per inch supporting a silicon oxide layer 20 and an aluminum oxide sheet 17, exhibits good resolution with a wide dynamic range with an accelerating voltage between coating 12 and target 13 of 100 to 500 volts. The mesh may have interstices of an area equal to one-half or considerably more than one-half of the area of the mesh. When tube 10 is operated in the vidicon mode, the video output of tube 10 is taken at mesh 18.

When tube 10 is operated in the orthicon mode, the video output is taken from collector 14.

It will be noted that electron beam 16 is directed toward target 13 on the side thereof on which mesh 18 is bare. Primary electrons from coating 12 are directed against the surface of sheet 17 opposite the surface thereof which lies in contact with dielectric 20.

In accordance with the foregoing, it is possible to construct target 13 with a dielectric sheet 17 of an extremely small thickness. The capacitance between the surface of sheet 17 which is charged by the primary electrons and mesh 18 is therefore very large. This permits the use of said proximity focus and a low zero primary accelerating voltage. This, in turn, prevents arcing and electric field distortion in the target 13 for a highly reliable resolution.

The high capacitance also increases the dynamic range of the target 13.

Still further, in spite of the fact that sheet 17 is very thin, target 13 has considerable structural integrity because of the proximity of sheet 17 to dielectric 20 and mesh 18, and the molecular bonds therebetween. A clamping device can also act as an additional or independent brace.

Although only a few specific embodiments of the invention have been described in detail, many changes and modifications will suggest themselves to those skilled in the art. The invention will therefore not be limited to the specific embodiments selected for this disclosure, the true scope of the invention being defined only in the appended claims.

What is claimed is:

1. A storage tube target comprising: a conductive wire mesh; a first dielectric evaporated on one side of said mesh having holes therethrough in registration with the holes in said mesh; and an imperforate sheet of a second dielectric bonded to said first dielectric in a position covering said registering holes.
- 10 2. The invention as defined in claim 1, wherein said first dielectric is a perforate evaporated layer of silicon monoxide having a maximum thickness of at least one and not more than fifty microns, said layer being bonded to both said mesh and said sheet.
- 15 3. The invention as defined in claim 2, wherein said sheet is an electroformed layer of aluminum oxide having a molecular bond to said evaporated layer, said sheet having a thickness of about 650 angstroms.
- 20 4. The invention as defined in claim 2, wherein said sheet is an evaporated layer of silicon monoxide, said sheet having a thickness of about 100 angstroms.
- 25 5. The invention as defined in claim 2, wherein said mesh has at least 500 wires per inch, said wires being circular in cross section.
- 30 6. The invention as defined in claim 2, wherein said sheet is made of potassium chloride.
7. The invention as defined in claim 2, wherein said sheet is made of magnesium oxide.
- 35 8. The invention as defined in claim 2, wherein said sheet is made of sodium bromide.
9. The invention as defined in claim 2, wherein said mesh is made of nickel and has 1000 lines per inch.
- 40 10. The invention as defined in claim 1, wherein said first dielectric is a layer of silicon dioxide having a maximum thickness of at least one and not more than fifty microns.
